UNITED STATES PATENT OFFICE.

ALBERT ERICSSON, OF OAKLAND, CALIFORNIA.

MUSIC-LEAF TURNER.

1,308,348.

Specification of Letters Patent.

Patented July 1, 1919.

Application filed June 23, 1917. Serial No. 176,628.

To all whom it may concern:

Be it known that I, ALBERT ERICSSON, citizen of the United States, residing at Oakland, in the county of Alameda and State of California, have invented certain new and useful Improvements in Music-Leaf Turners, of which the following is a specification.

This invention is an improved leaf turning attachment for music stands or rack-stands which is adjustable and collapsible and having means whereby a musician can, at will, turn sheets of music placed on the rack without inconvenience or interruption of his work.

15 In the accompanying drawings:

Figure 1 is a perspective view of my improved music stand. Fig. 2 is a broken view of the base thereof, parts being shown in central section. Fig. 3 is a vertical central section of a universal joint. Fig. 4 is a section of a detail. Fig. 5 is a vertical section of a top. Fig. 6 is a cross section on the line 6—6 of Fig. 2. Fig. 7 is a vertical side view of a detail. Fig. 8 is a vertical side view of a top. Fig. 9 is a vertical front view of a top. Fig. 10 is a side view of an arm clip. Fig. 11 is an end view of an arm clip. Fig. 12 is a vertical rear view of a keeper. Fig. 13 is a vertical front view of same. Fig. 14 is a top plan view of same. Fig. 15 is a broken perspective view of a washer within the top. Fig. 16 is a vertical central section of a rod actuator within the base. Fig. 17 is a similar view of an opposed rod actuator. Fig. 18 is a vertical side view of a portion of the mechanism within the base. Fig. 19 is a vertical side view of a piano with my invention attached. Fig. 20 is a front view of same. Fig. 21 is a vertical section of a modified base adapted to a piano. Fig. 22 is a plan view of same, parts thereof being broken away. Fig. 23 is a perspective view of same. Fig. 24 is a perspective view of a modified rod adapted to be engaged by 45 the modified base shown in Figs. 21, 22 and 23. Fig. 25 is a perspective view of a knee action lever.

Referring to the drawings, 1 indicates a base cap which is secured to one end of a vertical tube 2, within the opposite end of which is secured a collar 3, having three lugs 4, projecting outwardly. Pivotally connected to said lugs are ends of three braces 6, the opposite ends of which are pivoted, as shown 55 at 7, to legs 8, resting at their lower ends

upon a floor, or other support. The upper ends of said legs are pivoted as shown at 9 to a sliding collar 11, movable vertically upon a tubular standard 12, and securable upon said standard by means of a set screw 60 or thumb nut 13. The lower end of the standard 12, is threaded into the collar 3, as shown at 14. To the upper end of said standard is secured a collar 16. Through said collar 16 and tubular standard 12, is 65 threaded a thumb nut 17 adapted to firmly impinge against the outer surface of a tube 18 telescoping into standard 12 and which forms an extending member of said standard.

The upper end of the extension tube 18 is bent at a suitable angle, as shown at 19, in order to present the music to the eye of the musician at the proper angle. Near the end of the upper or bent portion of the tube 18, 75 is secured a stop collar 21, adapted to form a rest for a tubular casing 22, telescoped on the extension 18, and secured at any convenient height thereon by a set screw 23, passing through said tube 22 and a collar 24 80 thereon. Slidable on the tube 22 is a collar 26 through which is threaded a set screw 27. The purpose of the collar 26 is to furnish a support for a music rack 25, and it is prevented from turning upon the tube 22 by a 85 pin 28, which passes through the collar, and is slidable vertically in a groove 29, in the outward rear surface of the tube 22.

The music rack 25 is of usual construction, except in its central upright member 32, 90 which is notched as shown at 33, forming thereon a wedge or taper adapted to engage in a tapering slot 34 in the collar 26. To the top of the tube 22 is screwed one end of a sleeve 36, held from turning thereon by a 95 screw 37. Into the opposite end of the sleeve 36 is threaded a cap plug 38.

Through apertures 39 in the sleeve 36, extend collapsible arms 42. The said arms are formed of sections hinged together, as shown 100 at 43, and their outer ends are curved downwardly at right angles, as shown at 44, the downturned ends being provided with spring clips 46 having rubber lining pads 45, adapted to grasp the sheets 47 of printed music.

105 It will be seen from this construction that the music stand is set up in the usual manner, the base 1 resting on the floor, and the tripod adjusted until the legs all rest upon the floor where they are secured by the set 110

screw 13. The rack is then put in place, the printed music placed thereon and the clips 46 attached to the respective sheets. The turning of the sheets is accomplished by a 5 mechanism, hereinafter described, within the tubular standards and controlled and operated by collapsible pedals 48 and 49.

Within the tube 2 at the base thereof is secured a bearing member 51 which is released as shown at 52, 53 and 54. The recess 54 is internally threaded to receive a plug 56, having a hole therein through which freely passes a shaft 57, having a reduced portion 58, upon which is swaged a disk 59. 10 The lower surface of said disk 59 and the outer surface of the reduced portion of the shaft 58, bear against ball bearings 61 revolvable in the recess 53.

Surrounding the shaft 57 is a coiled spring 20 62, having its bearing at the lower end on the bearing member 51 and at its upper end abutting against the lower end of a casing 63. The said casing 63 is internally threaded at each end to receive plugs 64 and 66 25 which are secured to the walls of the casing 63 as shown at 67.

The casing 63 is divided into two separate compartments, by a washer or partition 68, inserted through a slot in the side of the 30 casing 63, and suitably secured within said casing. The said washer has a hole in its center of sufficient size to permit the free passage of the shaft 57. In the lower compartment of the casing 63, is a collar 69 35 which surrounds the shaft 57, the said collar being internally threaded with a quick acting thread, as shown at 71, adapted to engage in a helical groove 72, in the shaft 57. In the upper compartment of the casing 63, is a collar 73, similar to the collar 69, but in an inverted position, and with its internal thread 74, in the opposite direction from that of the thread 71. See Figs. 16 and 17. The thread 74 engages a helical 40 groove 76, in the shaft, similar in form to the groove 72, but running in the opposite direction. It will be seen from this construction, that if the casing 63 is depressed against the spring 62, and the collar 73 is held securely, and the collar 69 left free to rotate in engagement with the groove 76, the shaft 57 will be rotated to the left by reason of the engagement of groove 72 with collar 73; while if the collar 69 is held and 55 the collar 73 is left free to rotate in engagement with groove 72, the shaft 57 will rotate to the right.

Within the upper compartment of the casing 63, is a collar or depressor 77, through 60 which passes freely the shaft 57. The said depressor 77 is provided with an annular groove 78, designed to engage extensions 81, of the vertical arms of pedals 82, pivoted in grooves 83 in the casing 63, as shown at 84, 65 Fig. 18. The vertical members 82 of the

pedals 48 and 49 are slidable in slots 86 in the tube 2. The vertical members of the pedals 82 also have inwardly projecting teeth 87, placed and adapted to engage respectively teeth 88 and 89, on the perimeters 70 of the collars 69 and 73, if the said pedals are depressed against springs 91 secured in holes in the vertical members of the pedals. In Fig. 2 the tooth 87 is shown normally ready to engage teeth in the collar 73, when the spring 91 is depressed. In that pedal not shown, or in that portion of the tube which is cut away, the tooth 87 is placed in the lower compartment to engage teeth on the collar 69. The pedals 48 and 49 have depending or collapsible members 82^a pivoted to the vertical members as shown at 92. It results from this construction that when the left pedal is depressed the shaft 57 is rotated to the left, and if the right pedal is 85 depressed the said shaft is rotated to the right.

To the upper end of the shaft 57, is rigidly secured a cap 93, which has in its central portion a square hole, to receive one end 90 of a square shaft 94, which is secured to the cap 93, as shown at 96, causing said square shaft to rotate with the shaft 57. The other end of the square shaft 94, projects above the end of the pipe or tubular standard 12, 95 and is engaged by a square hole in a plug 97, secured within a pipe 98. The pipe 98 extends upwardly to the bent portion of the pipe 18, where it has secured in its end, a plug 99 (Fig. 3) which is attached to a universal joint of the usual construction, composed of balls 101 and links 102. The plug 99 has an annular groove 100, to receive a set screw 105, intended to prevent the plug from moving vertically. The upper end of 100 the said universal joint is attached to a plug 103, having a square projecting portion 104, which is adapted to enter and transmit motion to a plug 106, secured in one end of a pipe 107, rotatable within the tube 22. 110

Secured within the other end of said pipe 107, is a plug 108 (Fig. 5) to which is rigidly connected, as shown at 109, one end of a twisted strip of metal, forming an actuator 111, which is twisted as shown at 112, and has secured to its other end a pin 113, revolvable in a hole in a plug 114, which is threaded into the sleeve 36. The said pin is threaded and secured in place by lock nuts 116, above a washer 117. A portion of the actuator 111, is surrounded by a cylindrical tube 118, the ends of which are closed by plugs 119 (Figs. 4 and 5) having slots 121 to fit the metal strip of the actuator. It will be seen that when the actuator is rotated, the tube 118 will rise or fall accordingly as the actuator is rotated to the right or left, because of the slot 121, which follows the convolutions of the actuator 111. This vertical movement is timed and controlled by the set screw 37, 130

having a projection 123, which engages a double bayonet annular groove in the outer surface of the cylinder 118. The said cylinder 118 is provided with two pairs of projecting pins 124, which are designed to engage and rotate any pair of a series of pairs of pins 126, projecting inwardly from washerlike disks 127, rotatable within the sleeve 36. In the said washers are threaded 10 the ends of the collapsible arms 42, which arms may be rotated through 180° of a circle because of the solts 39, in the sleeve 36.

Interposed between the disks 127 (Fig. 15) are washers 128, which are prevented from 15 rotating in the sleeve 36, by projections 129, which fit in grooves 131, in the surface of the inner wall of said sleeve 36, as shown in Fig. 15.

From the foregoing it will be readily understood that in operation, the musician can 20 turn the printed pages by a pressure of the foot upon either pedal. Accordingly as the right or left pedal is depressed motion is imparted to one of the arms 42 which turn 25 through half a circle carrying the clip 46 with the printed page. For instance depression of pedal 82 draws down the casing 63 and simultaneously locking collar 73, thereby causing the shaft 57 to rotate. Such rotation is communicated to actuator 111, 30 through the connections 94, 97, shaft 98, collar 99, flexible shaft 101, 102, connections 104 and 106, and the tubular shaft 107. As the actuator 111 is rotated, it carries the control 35 member 118, and the disk 127 with which said member is engaged, until a vertical portion of the groove in the control member comes opposite screw 123, whereupon the control member is caused to travel longitudinally until the pins 124 come opposite the 40 pins 126. By this time the rotation movement has ceased. The initial rotation of the control member swings the leaf engaging arm with which it is coupled, as will be readily understood.

In Figs. 1 to 18 inclusive, the improved music rack is illustrated in a form adapted 50 to stand upon a floor and be operated by the foot of a musician. In Figs. 19 to 25 inclusive, is illustrated a modified form of music rack, to be installed on a piano to be operated by the knees of the player.

In the modified form, the music stand is 55 cut on the line 19—19 of Fig. 1, the upper portion being of the same construction as hereinbefore described. The square shaft 94, extends through a bushing, revoluble in the lower end of the tube 18. The said shaft 94 has on its lower end a projecting 60 plug 136 (see Fig. 24), adapted to enter a recess 137, in a shaft 138, revolving in a barrel 139, the top of which is flush with the upper surface of the music shelf, as shown in Fig. 19 and 23. The mechanism for turning 65 the plug 138, which in turn imparts mo-

tion to the shaft 94, is of similar construction to that of the ordinary mortise lock, and is intended to be mortised into the lower side of the top board of the music shelf of a piano, as shown in Figs. 21 and 23.

The working parts are interposed between two plates 141, which are riveted together at the corners by posts 142, around which are tubular washers 143, adapted to space the said plates equally at the four corners. To 70 the upper plate 141, and in a hole therein is riveted the barrel 139, designed to extend through a hole bored in the upper surface of the music shelf, so that only the barrel and slotted shaft will be visible on the surface of said shelf. The lower plate 141 is longer than the upper and adapted to be secured against the lower face of the board supporting the music rack by screw eyes 145. Secured to the shaft 138 are two pinions 80 146, serrated on their periphery. The pinions 146 are serrated respectively right and left, in order that the teeth on the outer edge may be engaged and the shaft 138 rotated, by pawls 147 pivoted on gears 149, 90 and held in engagement with said teeth by springs 151. The gears 149 turn freely upon the shaft 138, and are engaged and rotated by segmental gears 152 and 153, pivoted as shown at 154 between the plates 141. The 95 said segmental gears 152 and 153 have extending arms 154 and 156, through the extremities of which are secured posts 157 and 158, which extend downward. The arm 156 is shorter than the arm 158 to allow it to 100 pass when rotated. Through holes in the posts 157 and 158, pass respectively cords 159 and 161, secured in said holes by means of set screws 162. Around the said set screws 162 are secured ends of coiled springs 105 163, the opposite ends of which are secured to the eyes of the screw eyes 145.

It will be seen from the foregoing construction that a pull on the cord 161, will cause the segmental gear 152, to engage the 110 gear 149, rotating it, and as the pawl 151 engages the gear 146, the shaft 138 will be rotated to the right, while a pull on the cord 159 will have the opposite effect, by reason of the same mechanism arranged to 115 operate in the opposite direction.

The cords 159 and 161 are passed around pulleys 164 and 165, and connected to ends of levers 166 by set screws 167. The levers 166 are pivoted near their central parts to 120 the under side of the keyboard of a piano and adapted to be reciprocated by means of depending fingers 168, pivoted at the forward ends of the levers 166 as shown at 169, and formed with jack-knife springs in 125 order that they may fold upward and out of sight when not in use.

Having thus explained the nature of the invention, and described an operative manner of constructing and using the same, al- 130

though without attempting to set forth all of the forms in which it may be made, or all of the forms of its use, the following is claimed:—

- 5 1. An improved leaf turner comprising a plurality of rotatable disks mounted to rotate independently and each having clutch pins, leaf-engaging arms attached to said disks, an actuator, a control member engaged 70 with said actuator and having clutch pins complementary to the pins of said disks, and means for imparting movement to said actuator.
- 10 2. An improved leaf turner comprising a plurality of ring-like disks mounted to rotate independently, leaf-engaging arms attached to said disks, a rotatable actuator formed of a twisted strip of metal extended through said disks, a control member engaged with said actuator and positioned to travel through the disks, said control member having means to engage the disks, and means for imparting movement to the actuator. 75
- 15 25 3. An improvement in leaf turners comprising a plurality of ring-like disks mounted to rotate independently, leaf-engaging arms attached to said disks, a rotatable actuator formed of a twisted strip of metal 80 extended through said disks, a tubular control member inclosing a portion of said actuator and engaging the same, said control member being positioned to travel through said disks and having means to engage the disks, guide means for said control member, and means for imparting movement to said actuator. 85
- 20 4. An improvement in leaf turners comprising a stand, a tubular casing supported 90 by said stand, a shaft rotatably mounted within said casing, an actuator connected with said shaft and located within said casing, leaf-engaging arms having their ends mounted within said casing, a control member engaged with said actuator and having means for engaging said arms, said control member being of tubular form inclosing said actuator, and means for selectively rotating said shaft in either direction. 95
- 25 50 5. A music leaf turner comprising a stand having a tubular base, an actuator casing supported by said stand, an actuator mounted within said casing, a rotatable shaft having one end connected with said actuator 100 and the other end within said base, leaf-engaging arms operated by said actuator, a collar within said base, said collar being rotatably and reciprocally mounted upon said shaft, and means whereby said collar may be locked against rotation, said collar and said shaft having complementary means for effecting rotation of the shaft. 110
- 55 60 6. A music leaf turner comprising a stand having a tubular base, an actuator casing supported by said stand, an actuator mounted within said casing, a rotatable shaft having one end connected with said actuator and the other end within said base, leaf-engaging arms operated by said actuator, a pedal casing within said base, a collar within said pedal casing and reciprocally and rotatably mounted upon said shaft, said collar and said shaft having complementary means for effecting rotation of said shaft, a spring acting against said pedal casing to maintain the same in a normal position, and a pedal connected with said pedal casing to depress the latter against the tension of said spring, said pedal having means for locking said collar. 120
- 65 7. A music leaf turner comprising a stand having a tubular base, an actuator casing supported by said stand, an actuator mounted within said casing, a rotatable shaft having one end connected with said actuator and the other end within said base, leaf-engaging arms operated by said actuator, a pedal casing within said base, collars within said 125

pedal casing and reciprocally and rotatably mounted upon said shaft, said collars and said shaft having complementary means whereby the shaft may be rotated in either 5 direction, a spring acting against said pedal casing to maintain the same in a normally elevated position, and pedals connected with

the pedal casing to depress the latter against the tension of said spring, said pedals being positioned opposite the respective collars 10 and having means for locking the collars.

In testimony whereof I affix my signature.

ALBERT ERICSSON.
